JOSEPH O. BEAZLEY, OF BALTIMORE, MARYLAND.

DUSTLESS POLISHING-MOP.

1,112,190.

Specification of Letters Patent. Patented Sept. 29, 1914.

Application filed October 6, 1913. Serial No. 793,701.

To all whom it may concern:

Be it known that I, JOSEPH O. BEAZLEY, a citizen of the United States, residing at Baltimore, State of Maryland, have invented, a new and useful Dustless Polishing-Mop, of which the following is a specification.

The invention relates to improvements in mops.

The object of the present invention is to improve the construction of mops and to provide a simple, inexpensive and efficient mop of strong and durable construction equipped with a head of soft material designed particularly for cleaning and polishing hard wood floors, furniture and other finished wood work and adapted to pick up and hold the dust without scattering or stirring the same.

A further object of the invention is to provide a dustless polishing mop of this character capable of automatically adjusting itself to the angle of a surface and of retaining itself positively in its various adjustments so that there will be no liability of the mop head wabbling and thereby interfering with the proper operation of the same or shaking the collected dust from it.

With these and other objects in view the invention consists in the construction and novel combination of parts hereinafter fully described, illustrated in the accompanying drawing, and pointed out in the claims here-to appended; it being understood that various changes in the form, proportion, size and minor details of construction, within the scope of the claims, may be resorted to without departing from the spirit or sacrificing any of the advantages of the invention.

In the drawing:—Figure 1 is a perspective view of a polishing mop constructed in accordance with this invention, the handle being removed. Fig. 2 is a central longitudinal sectional view of the mop, the handle being partly broken away. Fig. 3 is a transverse sectional view on the line 3—3 of Fig. 2. Fig. 4 is a detail perspective view of the spring plate. Fig. 5 is an enlarged detail sectional view through one of the spring loops showing in full lines the position of the parts before the loop is flexed, and illustrating in dotted lines the flexing of the loop.

Like numerals of reference designate corresponding parts in all the figures of the drawing.

In the accompanying drawing in which is illustrated a preferred embodiment of the invention, the mop head comprises a substantially oblong back 1 and a soft flexible body composed of longitudinal rows of closely arranged pendant twisted strings or cords 2 and having a concavity 3 at its lower face and provided in advance and at the rear of the center with hollow portions 4 formed by omitting portions of the rows of the strings or cords and co-acting with the concavity 3 to tend to create a suction when the mop head after being pressed against or laid upon a surface is lifted therefrom and causes the dust to be picked up by the mop without stirring or scattering the dust. The concavity 3, which is elongated, forms a hollow or recess which is curved both longitudinally and transversely and bounded by outer side and end marginal portions, the concavity terminating short of the sides and ends of the body, as clearly illustrated in Figs. 2 and 3 of the drawing, and when the mop is placed on a surface it is adapted to absorb or pick up the dust and will hold the same until shaken out or washed. The strings or cords extend over strips 5 and are secured in a recess 6 in the lower face of the back of the mop, but any other suitable fastening means may be employed for securing the soft body of the head to the back 1 thereof. No claim is made in the present application to the particular construction of the brush head.

The back 1 of the mop head is preferably constructed of wood and in order to prevent it from scratching or otherwise injuring furniture or other polished surfaces, it is provided with a soft marginal buffer 7 preferably consisting of a piece of braided or twisted rope and arranged in marginal grooves 8 in the side and end edges of the back of the mop. The marginal buffer 7 may be secured within the groove in any suitable manner and enables the brush of the mop to be moved over a polished floor in close proximity to the furniture of a room or apartment without danger of scratching the same. The back 1 of the mop head is adjustably connected with handle 9 by means of a pair of arms 10 and a spring plate 11 secured to and extending across the back 1 of the mop head and provided with terminal approximately U-shaped spring bends 12 receiving terminal pivots 13 of the arms 10. The arms 10 are preferably formed from a

single piece of stout wire or wrought metal bent to form a straight shank 14 and preferably twisted at the outer portion thereof at 15 adjacent the inner or rear portions of the arms 10. The straight shank which is composed of two sides is slidable into and out of the bore or opening 17 of a hollow handle 9, which is provided with a clamping screw 18 or other suitable device for adjustably securing the shank in the hollow ring 16. The handle may be constructed of wood or any other suitable material and the clamp screw 18 is preferably mounted in a threaded perforation of a reinforcing sleeve or ferrule 19.

The substantially U-shaped bends 12 of the spring plate 11 are located at opposite sides of the back 1 of the mop head and they are composed of inner and outer sides and a curved connecting portion. The inner sides of the spring bends are provided with substantially circular bearing openings 20 and the outer sides have elongated openings or slots 21. The pivots 13 which are formed integral with the arms 10 extend outwardly therefrom and are arranged at an obtuse angle thereto, being disposed at an angle to each other. The inner portions of the pivots adjacent to the arms are received within the substantially circular openings 20, while the outer portions of the pivots operate in the elongated openings or slots 21 of the outer sides of the spring bends which are free. When the arms 10 which preferably diverge outwardly are arranged flat against the back 1 of the mop head there is comparatively little friction or binding action of the pintles in the openings 20 and 21 of the spring bends; but the upward or outward movement of the arms 10 from such position against the back of the mop carries or causes those portions of the pivots operating in the elongated openings or slots 21 to swing through an arc of a circle, whereby the spring bends are flexed and are caused to bind against the pivots at spaced points, the binding action increasing as the arms are swung away from the back. The pivotal connection between the arms 10 and the mop head enables the latter to automatically adjust itself to the various surfaces operated on, and the binding action between the angularly disposed pivots and the spring bends retains the mop head in its adjusted position with relation to the handle and the arms and prevents the mop head from wobbling. The outward swinging of the arms on their pivots forces the outer sides or portions of the spring bends toward the back 1 of the mop, and the inward swinging permits the springs to re-

cede from the back 1. This springing of the bends provides a practical frictional device of great strength and durability for adjustably connecting the handle with the mop head. A spring plate of any desired strength may be employed to secure the desired binding action on the pivots.

What is claimed is:

1. A mop of the class described comprising a mop head, a spring plate connected with the mop head and provided with spring bends having opposite openings, and a handle having arms provided with pivot portions mounted in the openings of the said bends and arranged to flex the said bends and create a binding action on the said pivot portions whereby the mop head is adjustably secured in its pivotal movement. 70

2. A mop of the class described, comprising a mop head, a spring plate provided with spaced approximately U-shaped bends having free outer portions, and a handle provided with pivot portions extending through the bends of the spring plate and arranged to flex the free portions thereof to produce a binding action on the pivots for holding the mop head in various positions with relation to the handle. 80

3. A mop of the class described, including a mop head, a spring plate carrying the mop head and provided with approximately U-shaped bends composed of inner and outer sides, the inner sides being provided with substantially circular openings and the outer sides having elongated openings, and a handle provided with pivot portions arranged at an angle to each other and operating in the said openings and adapted to flex the spring bends when the handle is swung outwardly from the mop head whereby the latter is held in different positions with relation to the handle. 90

4. A mop of the class described, including a mop head, a transverse plate secured to the mop head and provided with terminal approximately U-shaped bends having openings in its inner and outer sides, a mop handle, and arms extending from the handle and having terminal pivots arranged at an angle to each other and operating in the openings of the spring bends and adapted to flex the latter to produce a binding action on the pivots to retain the mop head in various positions with relation to the handle. 110

In testimony, that I claim the foregoing as my own, I have hereto affixed my signature in the presence of two witnesses.

JOSEPH O. BEAZLEY.
